[57] CLAIM

The ornamental design for pull tab for slide fastener, substantially as shown and described.

DESCRIPTION

FIG. 1 is a front elevational view of a pull tab for slide fastener showing my new design;

FIG. 2 is a side elevational view thereof, the opposite side being substantially a mirror image thereof;

FIG. 3 is a bottom plan view thereof; and

FIG. 4 is a top plan view thereof.

Fig.1.

Fig.2.

Fig.3.

Fig.4.
